(57) **CLAIM**

I claim the ornamental design for an amplifier for an automobile, as shown and described.

DESCRIPTION

FIG. 1 is a top perspective view of an amplifier for an automobile of the present invention;

FIG. 2 is a front view thereof;

FIG. 3 is a side view thereof;

FIG. 4 is a side view thereof, opposite that shown in FIG. 3;

FIG. 5 is a top view thereof;

FIG. 6 is a rear view thereof; and,

FIG. 7 is a bottom view thereof.

The broken line showing of the amplifier for an automobile is included for the purpose of illustrating environmental and forms no part of the claimed design.
